(57) CLAIM

The ornamental design for a shutter with solar cell lamellae, as shown and described.

DESCRIPTION

FIG. 1 is a perspective view of a shutter with solar cell lamellae.

FIG. 2 is a front elevation view of the shutter with solar cell lamellae of FIG. 1.

FIG. 3 is a back elevation view of the shutter with solar cell lamellae of FIG. 1.

FIG. 4 is a top plan view of the shutter with solar cell lamellae of FIG. 1.

FIG. 5 is a bottom plan view of the shutter with solar cell lamellae of FIG. 1.

FIG. 6 is a right side elevation view of the shutter with solar cell lamellae of FIG. 1; and,

FIG. 7 is a left side elevation view of the shutter with solar cell lamellae of FIG. 1.

The broken lines shown represent unclaimed subject matter and form no part of the claimed design.
